[57] CLAIM

The ornamental design for an upholstered screen, substantially as shown and described.

DESCRIPTION

FIG. 1 is a perspective view of an upholstered screen showing my design wherein the undisclosed faces thereof are the same in appearance as the faces shown. FIG. 2 is a top plan view of the upholstered screen of FIG. 1;

FIG. 3 is an enlarged fragmentary perspective view showing the lower right corner portion of the upholstered screen of FIG. 1;

FIG. 4 is an enlarged fragmentary view showing a portion of the upholstery fabric in greater detail;

FIG. 5 is a modified form of the upholstered screen disclosed in FIG. 1, the faces of the screen not shown being the same in appearance as the faces shown; and FIG. 6 is a top plan view of the upholstered screen of FIG. 5.

FIG. 1.

FIG. 2.

FIG. 3.

FIG. 4.

FIG. 5.

FIG. 6.
